FIREARM BENCHREST

Malcolm E. Allison, 4902 Enyart St., Houston, Tex.

Filed Oct. 2, 1964, Ser. No. 82,000

Term of patent 14 years

(Cl. D30—1)

FIGURE 1 is a side elevational view of a firearm benchrest, showing my new design.

FIGURE 2 is a perspective view thereof.

FIGURE 3 is a perspective view of the side opposite to that shown in FIGURE 2.

FIGURE 4 is a front elevation view thereof.

FIGURE 5 is a top plan view thereof.

FIGURE 6 is another side elevational view of the firearm benchrest, showing the rest supports in an alternate position.

The essential features of the design reside in the portions shown in solid lines.

The depiction of the rifle and the arm and pistol in the drawings is shown for illustrative purposes only.

I claim:

The ornamental design for a firearm benchrest, as shown and described.
